UNITED STATES PATENT OFFICE.

DENNIS KELLY, OF CINCINNATI, OHIO, ASSIGNOR OF ONE-HALF TO JOSEPH W. BREWSTER, OF SAME PLACE.

COAT AND CLOAK HOOK.

SPECIFICATION forming part of Letters Patent No. 271,640, dated February 6, 1883.

Application filed May 27, 1882. (No model.)

To all whom it may concern:

Be it known that I, DENNIS KELLY, a citizen of the United States, residing at Cincinnati, in the county of Hamilton and State of Ohio, have 5 invented a certain new and useful Improved Coat and Cloak Hook; and I do hereby declare that the following is a full, clear, and exact description of the invention, which will enable others skilled in the art to which it applies to make and use the same.

The accompanying drawing illustrates my invention.

Heretofore coat and cloak hooks have been made of wire consisting of two outwardly-diverging wires from each side of the center, bent and shaped to the general angles of the garment which is to hang thereon; but this form or style of hook I do not claim.

My improved coat and cloak hook consists 20 of a frame made of the single wire A and spirals B and B', as shown in the drawing forming a part of this specification, the wire A forming a loop at the top to catch over a nail or hook in the wall on which to suspend the coat hook, and by gradual curves continuing from each side of the loop, forming the shape or outline similar to that formed by a person's shoulders or the garment intended to hang upon it, and continuing across from the lower ends or 25 angles to form the brace by which the lower ends of the hook are kept from being inclined or bent in by the weight of the garment.

The old style of double or diverging wire hooks is objectionable, because in garments 30 made of most kinds of cloth the longitudinal wires cause creases and marks where the garments rest upon the wires, especially when

hung where exposed to dust; but to obviate this objection I start a wire on each side of the loop at the top of the hook where the two 40 sides nearest converge and continue down the frame A of the hook, forming a spiral down each side of the frame, (shown in the drawing, B and B'), until the spirals reach the lower 45 points or angles at the corners of the frame, where the wire-frame turns to form the cross-brace, both sides or halves of the hook being alike, the spirals being fastened to the frame A in any suitable manner, thus forming a broad and round hook with many surfaces, upon 50 which the weight of the garment may be distributed, preserving the coat, cloak, or other garment in better shape and obviating the objection to the former styles mentioned.

The accompanying drawing illustrates the 55 device very accurately, and the advantages of my hook and its method of construction are obvious.

I am aware that coat and vest hangers have formerly been used with spirally-wound arms 60 or yokes; but this I do not broadly claim.

Having thus described my invention, what I claim, and desire to secure by Letters Patent, is—

The wire coat and cloak hook consisting of 65 the combination of the wire frame A, passing through and supporting the wire spirals B and B', with the wire spirals B and B', substantially as shown and described, and for the purpose specified.

DENNIS KELLY.
